UNITED STATES PATENT OFFICE.

HERBERT MUNRO TAYLOR, OF TORONTO, ONTARIO, CANADA, ASSIGNOR OF ONE-HALF TO FRANK SUTCLIFFE, OF CONSHOHOCKEN, PENNSYLVANIA.

EARTH ANCHOR.

Application filed November 17, 1924. Serial No. 750,400.

To all whom it may concern:

Be it known that I, HERBERT MUNRO TAYLOR, a subject of the King of Great Britain, and a resident of the city of Toronto, in the 5 county of York, Province of Ontario, Dominion of Canada, have invented certain new and useful Improvements in Earth Anchors, of which the following is a specification.

10 My invention relates to improvements in earth anchors with more particular reference to that type having movable flukes and the object of the invention is to devise an improved anchor of this type which may be 15 readily constructed from sheet metal thus eliminating the undesirable features of anchors which are cast; a further object is to provide an anchor in which the force applied in the opening or expanding will 20 tend to be more completely and effectively utilized than hitherto and in which the tendency of the crosshead or top part of the anchor to rotate in the earth during its expanding movement is eliminated; a further 25 object is to so construct the parts as to provide the most effective bearing surface possible against the earth; and a still further object is to lower the cost of manufacture by a simplified construction.

30 Further objects will appear in the course of the following specification.

My invention consists in the construction and arrangement of parts, all as hereinafter more particularly described and illustrated 35 in the accompanying drawings in which:

Fig. 1 is a top plan view of an anchor constructed according to my invention, the parts being in the collapsed position.

Fig. 2 is a side elevation of Fig. 1, the 40 upper portion of the near radius arm being broken away.

Fig. 3 is a top plan view of the anchor in the expanded or open position.

Fig. 4 is a transverse section taken on the 45 line 4—4 of Fig. 3.

Fig. 5 is a view taken similar to Fig. 3 with certain parts omitted and other parts broken away to show the manner in which the flukes operate and are mounted upon the 50 crown of the anchor.

Fig. 6 is a detached plan view of one of the flukes used in my improved anchor.

Fig. 7 is a section taken on the line 7—7 of Fig. 6.

Fig. 8 is a perspective view of a sheet 55 metal crown used in my invention.

Fig. 9 is a face view of a flat metal strip from which a bushing used in my invention is formed.

Fig. 10 is a top plan view of the strip in 60 Fig. 9.

Fig. 11 is a top plan view of this bushing in its completed form.

Fig. 12 is a side elevation of this bushing, 65 the left hand portion shown in section.

In the drawings, like characters of reference indicate corresponding parts in the various views.

In the form of my invention illustrated, a 70 crown 1 is used which is formed from sheet metal.

This crown is of rectangular shape and two of its opposite edges 2—2 are bent upwardly and inwardly to form guideways 3 upon the upper face of the crown, the remaining two edges 4—4 being bent downwardly and inwardly to form guideways 5 upon the bottom face of the crown.

These bent edges 2—2 and 4—4 thus constitute marginal flanges forming marginal 75 guideways above and below the crown respectively, the guideways 3 being disposed at right angles to the guideways 5.

These guideways also provide pockets or 80 containers for grease or other lubricant.

The crown is also provided with a central orifice 6 which will be hereinafter referred to.

Anchor flukes 7, 8, 9 and 10 are associated with the crown 1, being arranged in two pairs, one pair 7—8 being mounted above the crown and the other pair 9—10 below the crown.

The pair 7—8 are slidably mounted within the upper guideways 3—3 and the pair 9—10 85 within the lower guideways 5—5.

The flukes are formed from flat metal sheets and those of each pair are arranged in superimposed relation so that they slide upon each other.

The flukes are further provided with central longitudinal slots 11 extending inwardly 90 from one end thereof slightly beyond the centre.

The flukes are further offset centrally at 12 (see Fig. 7 in particular) and are so arranged that each fluke of a pair occupies the uppermost position over approximately one half of its width and the undermost position over the remaining half of its width, this arrangement of the flukes being made possible by the slots 11 and the offsets 12.

The slots 11 in each pair of flukes register with each other and with the central orifice 6 in the crown.

The flukes are further provided with longitudinally disposed channels 13 which engage each other and constitute combined fluke guides and stiffening ribs.

A crosshead 14 is mounted above the crown and is connected to the outer end of each fluke by a comparatively wide flat strap 15 which straps constitute radius arms.

These straps could be provided with stiffening ribs if desired.

These straps are provided adjacent to each end with transverse slots 16 which slots are of suitable dimensions to prevent rotation of the crosshead.

Secured to each fluke adjacent to its outer end is a clip 17 and secured upon the under side of the crosshead 14 are four clips 18.

The clips 17 and 18 extend through the slots 16 in the straps 15 so that each fluke is positively connected to the crosshead and are shaped so as to give a double bearing at all times between the clips and straps as at A in Fig. 2.

A cylindrical bushing 19 is secured within a central orifice in the crosshead 14.

In the form illustrated, this bushing is of novel construction and is formed from a flat metal strap 20 upon one side of which are spaced protuberances 21. This strap is bent into cylindrical form so that the two ends come together.

The protuberances 21 are then spaced circumferentially about the outer face of the bushing and are disposed intermediately of its length.

In mounting the bushing 19 within the crosshead 14 the upper portion 22 (see Fig. 12) is inserted upwardly through the orifice in the crosshead until the protuberances 21 engage its under face.

The upper end of the bushing is then burred over at 23. This provides a very secure mounting for the bushing and also the protuberances 21 provide a bearing for the clips 18 which prevents movement of these clips.

This construction enables the crosshead and bushing assembly to be hot galvanized and insures a solid and secure job.

An anchor rod 24 carrying a nut 25 forming an enlargement at its lower end, extends through the slots 11 in the flukes, and the central orifice 6 in the crown and is an accurate sliding fit in the bushing 19, the nut

25 engaging the bottom faces of the lowermost flukes.

The construction and operation of my invention is as follows:

In Figs. 1 and 2 the anchor is shown in 70 the collapsed or closed position.

In using the anchor the usual hole of the same diameter as the collapsed diameter of the anchor is provided in the earth and the anchor mounted upon the rod 24 is inserted 75 into the hole in the collapsed position.

The flukes 7, 8, 9 and 10 are expanded by tapping downwardly upon the crosshead 14 which is slidable upon the rod 24. When this is done the crosshead moves downwardly upon the rod and through the medium of the radius arms 15, the flukes are expanded outwardly into the position illustrated in Figs. 3, 4 and 5.

By making the crosshead circular a striking face for the tampon bar is provided entirely around the anchor rod.

The outer ends of the flukes may be bevelled to facilitate movement outwardly through the earth.

It is to be particularly noted that the flukes of my anchor are arranged in two pairs, one pair comprising the two superimposed flukes 7-8 being arranged above the crown 1 and the other pair comprising the two superimposed flukes 9-10 being arranged below the crown.

By this disposition of the flukes the pressure is equalized and the movement of the flukes greatly facilitated. Also as the anchor expands, the friction between each pair of flukes gradually decreases which will compensate for the extra force gradually required to force the flukes further into the earth.

It is also to be noted that the movement of the flukes above the crown is at right angles to that below the crown.

An important feature of my invention resides in the manner of connecting the crosshead 14 to the flukes.

It is very important that this connection be of a positive nature so that the radius arms 15 can not become disconnected from the crosshead if accidentally struck by the tampon bar when expanding the anchor and by the manner in which the clips 17 and 18 engage the slots 16 this positive connection is obtained.

A further feature of my construction is that the force exerted by the arms 15 upon the flukes is strictly radial, and the flukes have no vertical or spiral climbing movement as is the case in many anchors hitherto used.

This direct radial thrust is very important since it eliminates all tendency for the crosshead to rotate when the anchor is being expanded in the earth, and thus the entire force exerted upon the crosshead is effec-

tively utilized in forcing the flukes radially outward. This is not the case where there is a tendency for the anchor to rotate.

This tendency for the anchor to rotate when being expanded in the earth has been a disadvantageous feature in anchors of this type hitherto used.

The simplicity of my construction will be evident as it will be noted that the entire anchor may be formed from sheet metal, the crown 1 being of very simple construction and the flukes simply being slidably mounted above and below the crown.

The anchor rod 24 which passes freely through the crown, flukes and crosshead also serves directly as a guide for the flukes.

By making the radius arms 15 in the form of wide flat straps a much more effective bearing surface is presented to the earth than when these straps are in the nature of rods.

From the foregoing it will be apparent that I have devised valuable improvements in anchors of this type by which the objects of my invention have been attained.

Various modifications may be made in my invention without departing from the spirit thereof or the scope of the claims and therefore the exact forms shown are to be taken as illustrative only and not in a limiting sense and I desire, that only such limitations shall be placed thereon as are imposed by the prior art or are specifically set forth in the appended claims.

What I claim as my invention is:

1. In an earth anchor, in combination, a substantially flat crown provided with marginal guideways, on opposite faces thereof, and flukes associated with the crown and slidably transversely thereof in said guideways.

2. In an earth anchor, in combination, a substantially flat crown provided with marginal guideways, on opposite faces thereof, the guideways on one face of the crown disposed at right angles to those on the outer face, and flukes associated with the crown and slidably transversely thereof in said guideways.

3. In an earth anchor, in combination, a substantially flat crown provided with in-turned marginal flanges forming guideways on opposite faces of the crown, and flukes associated with the crown and slidably transversely thereof in said guideways.

4. In an earth anchor, the combination with a crown, of flukes slidably carried thereby on opposite faces thereof.

5. In an earth anchor, the combination with a crown, of flukes slidably carried

thereby on opposite faces thereof, the fluke movement over one face of the crown being at right angles to that over the other face.

6. In an earth anchor, in combination, a substantially flat crown provided with in-turned marginal flanges forming guideways, on opposite faces of the crown, and superimposed flukes associated with the crown and slidably transversely thereof in each set of said guideways, the fluke movement over one face of the crown being at right angles to that over the other face.

7. In an earth anchor, the combination with a crown, of plates forming superimposed flukes carried by the crown and slidably in opposite directions longitudinally of each other and across the crown, the plane of the flukes offset centrally so that each fluke occupies the uppermost position over one portion of its width and the undermost position over the remaining portion of its width.

8. In an earth anchor, the combination with a crown, of plates forming superimposed flukes carried by the crown and slidably in opposite directions longitudinally of each other and across the crown, the plates formed with longitudinally disposed engaging channels constituting combined fluke guides and stiffening ribs.

9. In an earth anchor, a substantially rectangular crown formed from a metallic sheet, two opposite edges of which are turned upwardly to form marginal guideways upon the upper face of the crown, and the remaining two edges of which are turned downwardly to form marginal guideways upon the lower face of the crown.

10. In an earth anchor, a crown formed from a metallic sheet, two opposite edges of which are turned upwardly to form marginal guideways upon the upper face of the crown, and the remaining two edges of which are turned downwardly to form marginal guideways upon the lower face of the crown, the upper and lower guideways disposed at right angles to each other.

11. In an earth anchor, a substantially rectangular crown formed from a metallic sheet, two opposite edges of which are turned upward and inwardly to form marginal guideways upon the upper face of the crown, and the remaining two edges of which are turned downwardly and inwardly to form marginal guideways upon the lower face of the crown.

HERBERT MUNRO TAYLOR.
